CRANKSHAFT BEARINGS FOR LOOMS

Edward F. Bahan, Greenville, S. C.

Application March 8, 1949, Serial No. 80,255

4 Claims. (Cl. 139—1)

1

This invention relates to a loom and more especially to a mounting for the crankshaft of the loom and a girt associated therewith for lending rigidity to the side frames of the loom.

Looms usually have side frames connected together by an arch and also connected together by means of a breast beam and front and rear lower girts. A crankshaft is usually rotatably mounted on the loom frames. The crankshaft has a pair of crank throws and has pitman rods connecting the same to swords which impart oscillation to the lay. The loom also has a cam shaft with picker cams thereon for operating pick shafts for quickly moving the picker sticks to propel the shuttle across the lay of the loom in a weaving operation.

Heretofore there have been various means provided for mounting the crankshaft of the loom and there have been additional strengthening and stiffening means extending crosswise of the loom immediately adjacent the crankshaft and being connected at opposite ends thereof to the proximate sides of the side frames. However, these girts have not proved satisfactory particularly due to the difficulty and the time and effort required in properly alining the bearings mounted on each of the side frames of the loom for rotatably supporting opposite ends of the crankshaft. Furthermore, during operation of the loom, the vibrations present make it difficult to keep these bearings in alinement with each other.

It is therefore an object of this invention to provide a pair of cast bearing units which are adapted to be mounted on the proximate sides of the side frames of the loom and each of which is provided with a pair of semi-circular grooves disposed in exact alinement with each other and between which the cranks adjacent each end of the crankshaft are adapted to pass and to further provide a pair of bearing caps for each of the cast bearing units, having an inverted semi-circular cavity or longitudinally extending groove therein which coincides with the longitudinally extending semi-circular groove in the cast bearing unit and which are removably secured to the cast bearing unit. The first-named semi-circular cavities are cut simultaneously in each of the cast bearing units thus insuring alinement between the semi-circular grooves in each of the cast bearing units.

It is another object of this invention to provide a girt which is adapted to extend transversely of the loom directly beneath the medial portion of the crank shaft and to further provide means for removably securing the opposite ends of the

2

girt to the proximate ends of the cast bearing units, the cast bearing units each having inwardly extending portions which extend beneath the opposite ends of the girt and the overlapping portions of the girt having keyways therein for slidale reception of the keys mounted in suitable keyways in the underlapping portions of the cast bearing units, these keys being mounted in the cast bearing units in exact parallel alinement with the axis of the semi-circular bearing grooves in the cast bearing unit, as a result of which the cast bearing units at opposite ends of the loom are held in accurate alinement with each other, thus insuring that the bearing in which the crankshaft is mounted will wear evenly throughout their length and also serving to lend rigidity to the side frames of the loom to thereby permit the loom to be run at relatively high speeds without any undue vibration. Thus the productive capacity of looms equipped with this improved mounting and the girt for the crankshaft is greatly increased, and stoppages for re-alinement of the crank shaft bearings is eliminated.

Some of the objects of the invention having been stated, other objects will appear as the description proceeds, when taken in connection with the accompanying drawings, in which

Figure 1 is a top plan view of a loom with parts in section and showing the improved girt with the cast bearing units mounted thereon, but omitting the grease fittings;

Figure 2 is a vertical sectional view taken substantially along the line 2—2 in Figure 1 and showing a loom equipped with the new girt and one of the cast bearing units and with some of the usual parts of the loom being omitted, the grease fittings associated with the bearing unit being omitted;

Figure 3 is a vertical sectional view taken substantially along the line 3—3 in Figure 2 showing how the supports for the center bearing blocks for the cam shaft are connected to the improved girt and showing the cast bearing units at opposite ends thereof but omitting the grease fittings;

Figure 4 is an exploded isometric view showing the cast bearing unit at the right-hand side of Figures 1 and 3 removed from the loom and showing the grease fittings in the bearing caps associated therewith;

Figure 5 is an enlarged vertical sectional view showing the manner in which the semi-circular bearing members are mounted in the cast bearing unit and being taken substantially along the line 5—5 in Figure 1, but omitting the loom frame and the crankshaft;

Figure 6 is an enlarged top plan view of the right-hand central portion of Figure 1, but omitting the crankshaft to clarify the manner in which the girt is secured to the cast bearing unit;

Figure 7 is an enlarged vertical sectional view taken along the line 7-7 in Figure 5.

Referring more specifically to the drawings, the numerals 10 and 11 indicate the two side frames of a loom which are usually secured together by front and rear bottom girts 12 and 13, respectively. The loom, of course, has a warp beam 14 mounted thereon from whence the warp is drawn to a conventional sand roll 15 and thus to a suitable cloth take-up mechanism, not shown. The loom also has a rocker shaft 17 with a pair of swords 18 oscillatably mounted at their lower ends on the rocker shaft 17 and supporting a lay 20 and a reed cap 21 on the upper end thereof. A suitable reed 22 is mounted between the lay 20 and the reed cap 21. The loom also has a conventional cam shaft 24 having pick cams 25 fixedly mounted thereon which are adapted to engage the usual pick arms, not shown, which are instrumental in projecting the shuttle, not shown, across the upper surfaces of the lay.

Looms of this type are usually provided with a pair of spaced forwardly and rearwardly extending middle girts 27 which are connected at their front and rear ends to the front and rear girts 12 and 13, respectively, as by bolts 30 and these middle girts 27 support conventional auxiliary shaft bearing boxes 32 in which the opposite ends of a conventional auxiliary shaft 33 are rotatably mounted and which usually has the conventional harness cams, not shown, mounted thereon. This auxiliary shaft 33 also has an auxiliary shaft gear 35 fixedly mounted thereon which meshes with an idler gear 36 (Figure 2) driven by a conventional harness change gear 37 fixedly mounted on the cam shaft 24.

The cam shaft 24 is rotatably mounted in the usual bearings 40 suitably secured to opposite sides of the loom and the medial portion of the cam shaft 24 is rotatably mounted in bearing blocks 42 and 42'. It may be observed in Figure 3 that the bearing block 42 is secured as by bolts 44 (Figure 2) to a center box bracket 43. Parts associated with the bearing block 42' being identical to parts associated with the bearing block 42 will therefore bear like reference characters to the parts associated with the bearing block 42 with the prime notation added.

The center box bracket 43, at the right-hand side of Figure 3 extends downwardly from the bearing block 42 and has an off-set downwardly extending portion 46 integral therewith the left-hand surface of which engages the right-hand middle girt 27 and the right-hand surface (Figure 3) of which engages a foot member 47, the lower end of which is adapted to rest on the floor which supports the loom. The foot member 47 has a projection 50 integral therewith which is penetrated by a vertically disposed adjustment screw 51 which engages the lower edge of the downwardly projecting portion 46 integral with the center box bracket 43 for vertical adjustment of the center box bracket 43 so the upper surface of an L-shaped bracket 52, secured to the upper portion of the center box bracket 43 as by bolts 53, may engage a transverse girt member 55 which is a part of the present invention and will be later described in detail.

It may be observed in Figure 2 that the downwardly projecting portion 46 of the center box bracket 43 has vertical adjustment slots 57 there-

in which are adapted to be slidably penetrated by bolts 60 which also slidably penetrate the vertical portion of the middle girt 27 and the foot member 47 has slots therein which coincide with the slots 57 in the portion 46 of the center box bracket 43 and which are also penetrated by the bolt 60 to thus secure the center box bracket 43 and the foot member 47 to the middle girt member 27 after the center box bracket 43 and the foot member 47 have been adjusted relative to each other by the adjustment screw 51.

Referring to Figure 1 it may be observed that the girt 55 has a plurality of spaced longitudinally extending slots 62 therein, some of which are adapted to be slidably penetrated by bolts 63 and 63' for securing the brackets 52 and 52', respectively, to the transverse girt 55.

The transverse girt 55 is secured at opposite ends thereof as by bolts 64 and 64' to inwardly extending underlapping portions 65 and 65', respectively, of cast bearing units broadly designated at 70 and 70', respectively, to be later described in detail. The cast bearing units 70 and 70' rotatably support a conventional crank shaft 71 in a manner to be later described. The crank shaft 71 has crank throws 72 and 72' integral therewith to which one end of pitman rods 73 and 73', respectively, are pivotally connected, their other ends being pivotally connected to the swords 18. It might be stated that the loom also has a suitable arch bar 75 which is secured at each end thereof to the side frames of the loom by any suitable means such as bolts 76.

Heretofore, in many looms, the crankshaft 71 of the loom has been mounted in suitable bearings disposed in the top portions of the side frame 10 and 11. Usually there is provided with looms of this type a single bearing which is disposed on the remote side of the crank throws 72 and 72' and therefore there was nothing to support the middle portion of the crankshaft and this resulted in vibrations in the crankshaft thus making it impossible to speed up the picks per minute of the loom. In special instances, there have been provided cast members having removable bearings secured thereto, there being one of these bearings disposed adjacent each side of each of the crank throws 72 and 72' of the crankshaft 71. However, due to the fact that these bearings have been removable from the cast member, there has been no way by which the bearings could be accurately aligned longitudinally of the crankshaft of the loom with the result that the bearings may become worn unevenly throughout their length, or in some instances, may cause ridges or circular grooves in the crankshaft 71 thus requiring replacement of the removable bearings or the crankshaft or both after bearings of this type have been installed for a relatively short length of time.

The cast bearing unit 70' at the left-hand side of Figures 1 and 3 being identical to the cast bearing unit 70 at the right-hand side of Figures 1 and 3, with the exception of being opposite hand, only the cast bearing unit 70 appearing at the right-hand side of Figures 1 and 3 will be described, like parts on the cast bearing unit 70' bearing like reference characters to those appearing on the cast bearing unit 70 with the prime notation added.

Referring to Figures 3 and 4 it may be observed that the cast bearing unit 70 has a vertically disposed forwardly and rearwardly extending portion 80 having a plurality of irregularly spaced holes or slots 81 therein which are

adapted to be slidably penetrated by bolts 82 for securing the cast bearing unit 70 to the inner vertical surface of the side frame 10. The cast bearing unit 70 is, of course, secured to the inner vertical surface of the side frame 11 in like manner. Disposed above the vertically disposed portion 80 and extending outwardly therefrom is an integral bearing block portion 83 the lower surface of which is machined accurately for mounting on an outwardly projecting portion 84 which is an integral part of the conventional side frame member 10, there being a similar portion 84' integral with the side frame member 11. There are many models of looms which are not provided with the outwardly projecting portions 84 and 84' shown on the remote sides of the frame members 10 and 11 in Figure 3. In this case, the bearing portions 83 and 83' merely extend outwardly beyond the remote surfaces of the side frames 10 and 11.

Spaced apart from the bearing block portion 83 is a second bearing block portion 86 having a vertical end wall 87 remote from the bearing block portion 83. The bearing block portions 83 and 86 have alined semi-circular grooves 90 and 91 cut in their upper surfaces which are machined to accurately receive semi-circular concavo-convex longitudinally extending bearing members 92 and 93, respectively. Figure 5 shows the manner in which the bearing member 92 is mounted in the bearing block 83 to prevent endwise movement of the semi-circular bearing member 92. The semi-circular bearing 93 is mounted in the bearing block portion 86 in an identical manner and a showing of the same is not deemed necessary. It will be noted in Figure 5 that the bearing block portion 83 has a locking member 85 of soft metal, such as bronze or the like snugly mounted therein which has a restricted portion 88 projecting upwardly therefrom. The vertical length of the portion 88 is less than the thickness of the bearing member 92 and the member 92 is provided with a bore 96 which is adapted to be slidably penetrated by the portion 88 when the member 92 is placed in the semi-circular groove 90 to thus prevent endwise movement of the member 92 in the bearing block portion 83. The upper edges of the bearing members 92 and 93 are machined accurately on their respective axes and it may be observed in Figure 4 that the bearing block portions 83 and 86 are provided with longitudinally extending right angularly cut grooves 94 and 95, respectively, whose top surfaces are disposed in a horizontal plane coinciding with the axes of the bearing members 92 and 93, there being one of the grooves 94 and 95 at each side of the bearing members 92 and 93, respectively, the purpose of which will be later described.

The underlapping portion 65 at the inner side of the cast bearing unit 70 has a longitudinally extending keyway 100 cut therein which is machined in accurate parallel relation to the axes of the bearing members 92 and 93 and is adapted to slidably receive a key 101. Opposite ends of the girt member 55 are provided with longitudinally extending keyways 102 and 102' which are machined in accurate parallel alinement with each other and are cut in the lower surfaces of the end portions of the girt 55 and which are adapted to slidably receive the key 101 when the girt 55 is secured to the underlapping portions 65 and 65' of the cast bearing units 70 and 70', respectively.

It may be observed in Figure 4 that the under-

lapping portion 65 is provided with a plurality of bores 103 and the overlapping portion of the girt 55 is provided with slots or openings 104 which coincide with the bores 103 in the underlapping portions 65 for slidable reception of the bolts 64, heretofore described, which secure the girt member 55 to the cast bearing unit 70. It may be noted in Figures 4 and 6 that the ends of the girt 55 are provided with spaced pads 105, the vertical ends of which may be filed off when the girt 55 and the cast bearing units 70 and 70' are applied to looms whose side frames 10 and 11 are not far enough apart from each other to accommodate the girt 55 in its original length.

The cast bearing unit 70 (Figure 4) has an irregularly curved portion 106 which extends between the bearing block portion 86 and the vertically disposed portion 80 and it also has a rear vertically disposed wall portion 107 which extends between the rear portions of the bearing block portions 83 and 86 and extends downwardly and is curved inwardly as at 108 to lend rigidity thereto at its juncture with the vertically disposed portion 80. It is thus seen that the portions 80, 83, 86, 106 and 107 define an opening 109 through which the crank throw 72 is adapted to pass.

It will be noted in Figure 4 that the cast bearing unit 70 has horizontally disposed portions 111 and 112 adjacent the rear wall portion 107 and which are provided with slots 113 and 114, respectively for supporting other conventional parts of the loom, not shown, such as the warp stop motion which is not pertinent to the present invention and, consequently, is not shown in the drawings.

The upper surfaces of the bearing block portions 83 and 86 are machined accurately for reception of semi-circular caps 116 and 117, respectively, whose lower surfaces are also machined. The bearing caps 116 and 117 are provided with longitudinally extending inverted semi-circular grooves 120 and 121, respectively, which are milled for accurate reception of longitudinally extending semi-circular bearing members 122 and 123, respectively, which coincide with the semi-circular bearing members 92 and 93 in the bearing block members 83 and 86, respectively. It will be noted that the bearing caps 116 and 117 are provided with longitudinally extending ridges 125 and 126, respectively, there being one of these ridges adjacent each side of the semi-circular grooves 120 and 121, respectively, and which are accurately machined parallel to and in the same horizontal plane as the axis of the semi-circular bearing members 122 and 123, so they may seat accurately in the coinciding grooves 94 and 95 in the bearing block portions 83 and 86, respectively, thus insuring that the parts, when assembled, may be accurately alined.

The bearing blocks 116 and 117 are provided with outwardly projecting tab portions or flanges 130 and 131, respectively, at each side thereof, each of which has a hole 133 therein, the bearing block portions 83 and 86 each having vertically extending bores 134 therein, there being one of these bores 134 adjacent each side of the semi-circular bearing portions 92 and 93. The bores 134 coincide with the holes 133 in the bearing caps 116 and 117. The holes 133 in the bearing cap 116 and the holes 134 in the bearing block portion 83 are adapted to be slidably penetrated by bolts 140 for securing the bearing block portion 83 of the cast bearing unit 70 to the out-

wardly projecting portion 84 on the side frame member 10 and for securing the cap 116 to the portion 83.

It has already been stated that some looms are not provided with the projections 84 and 84'. It is manifest that the bolts 140 would then serve only to secure the cap 116 to the bearing block portion 83.

Bolts 141 slidably penetrate the holes 133 in the bearing cap 117 and the bores 134 in the bearing block portions 86 of the cast bearing unit 70 to thus secure the bearing cap 117 on the bearing block portion 86.

Referring to Figures 5 and 7, it may be observed that the semi-circular bearing member 122 is mounted in the groove 120 of bearing cap 116 in a manner similar to that in which the bearing member 92 is mounted in the block portion 83. A locking member 143 of soft metal, such as bronze or the like, is snugly mounted in the cap 116 and has a restricted portion 144 projecting downwardly therefrom. The vertical length of the portion 144 is less than the thickness of the semi-circular bearing member 122 and the member 122 is provided with a bore 145 which is adapted to be slidably penetrated by the portion 144 to prevent endwise movement of the bearing member 122 in the cap 116 when assembled. The bearing cap has a suitable grease fitting 146 threadably mounted therein and has a bore 147 therein which extends between the grease fitting and the locking member 143. The locking member 143 has a hole 150 therein through which the lubricant may pass from the bore 147 into the area defined by the semi-circular bearing member 122. The bearing member 123 is mounted in the cap 117 in a manner identical to that shown for the bearing member 122 and a further description of the same is not deemed necessary. The grease fitting associated with cap 117 is indicated at 151 in Figure 4. The locking members 85 and 143 also prevent the semi-circular bearing members 92 and 122 from rotating with the crankshaft 71.

In order to insure the desired relationship between the various machined surfaces on the cast bearing unit 70, a description of the manner in which the various surfaces are machined is believed to be in order. The initial surface to be machined is the vertical side of portion 80 which is adapted to engage the inner side of the side frame member 10. The cast bearing unit 70 is then placed in a suitable jig and the upper surface of the underlapped portion 65 is machined perpendicular to the right-hand surface of the portion 80 in Figure 3. The keyway 100 is then cut in the portion 65 at right angles to the portion 80 and then the upper surfaces of the bearing block portions 83 and 86 are machined in exact parallel relation to the upper surface of the portion 65, which would, of course, cause the upper surfaces of the portions 83 and 86 to be perpendicular to the right-hand surface of the portion 80. The lower surfaces of the bearing caps 116 and 117 having previously been machined, the bearing caps 116 and 117 are secured to the upper surfaces of the bearing block portions 83 and 86 in the manner described, after which the semi-circular grooves 90 and 91 in the cast bearing unit 70 and the semi-circular grooves 120 and 121 in the bearing caps 116 and 117 are machined simultaneously by the use of a single cutting tool, the axis of which would be parallel to the surfaces 83 and 86 in a horizontal plane

and parallel to the keyway 100 in a horizontal plane.

It has already been stated how the ends of the girt members 55 are machined and it is thus seen that accurate alinement of the bearing surfaces in the cast bearing unit 70 with the girt members 55 and with the bearing surfaces in the other of the cast bearing units 70' may be insured.

It is thus seen that I have provided a combination girt and crankshaft mounting for a loom comprising cast bearing units to which the girt may be removably secured before securing the cast bearing units to the side frame members of the loom and the cast bearing units having bearings therein for rotatably supporting the crankshaft at opposite sides of each of the crank throws. Means are further provided whereby accurate alinement of the various parts may be insured upon these parts being assembled and the girt, of course, tends to lessen vibration caused by the various driven parts of the loom.

In the drawings and specification there has been set forth a preferred embodiment of the invention, and although specific terms are employed, they are used in a generic and descriptive sense only, and not for purposes of limitation, the scope of the invention being defined in the claims.

I claim:

1. In a loom having side frames and also having a crankshaft, the said crankshaft having a pair of crank throws thereon, means for rotatably mounting the crankshaft between the side frames of the loom comprising a pair of cast bearing units adapted to be secured to the proximate surfaces of the side frames, the cast bearing units being provided with semi-circular bearing surfaces milled in their upper extremities, said bearing surfaces being disposed on the same axis and being adapted to rotatably receive the crankshaft on each side of the crank throws, bearing caps removably secured to the upper surfaces of the cast bearing units and having bearing surfaces at their lower extremities adapted to coincide with the bearing surfaces in the upper extremities of the cast bearing units, the proximate ends of the said cast bearing units having inwardly projecting portions integral therewith, each of the inwardly projecting portions being provided with a keyway, a key adapted to be slidably mounted in the keyway, a girt adapted to be secured at each end thereof to the upper surfaces of the inwardly projecting portions of the cast bearing units, said girt having a keyway at each end thereof disposed in coinciding relation with the keyways in the inwardly projecting portions of the cast bearing units and being adapted to slidably receive the upper portion of the corresponding keys, said keyways in the inwardly projecting portions of the cast bearing units and in the opposite ends of the girt being cut in accurate alinement with each other to thus insure accurate alinement of the cast bearing units with respect to each other.

2. In a loom having side frame members, each of said side frame members having an outwardly projecting portion near its upper end and intermediate its foremost and rearmost ends, said loom also having a crankshaft and said crankshaft having a pair of spaced crank throws integral therewith, means for rotatably supporting the said crankshaft comprising a pair of cast bearing units, each of said cast bearing units comprising a vertical portion, an outwardly extending bearing block portion integral with the vertical portion and having a semi-circular bear-

ing cavity milled therein, the lower surface of the outwardly extending bearing portion being machined and being adapted to rest on the outwardly projecting portion of the side frame of the loom, a cast bearing block portion spaced inwardly from the first-named bearing block portion and also being integral with the cast bearing unit and having a semi-circular bearing milled therein whose axis is in alignment with the other semi-circular bearing cavity, each of said cast bearing units having a front portion and a rear wall portion integral therewith spanning the distance between the first named and second named bearing block portions and defining an opening through which the crank throw at the 15 adjacent end of the crankshaft is adapted to pass, bearing caps removably secured to the upper surfaces of each of the said bearing block portions to form the upper halves of bearings for rotatably supporting the crankshaft, means for lending rigidity to the side frame members of the loom in cooperation with the means for rotatably supporting the crankshaft comprising a girt member, underlapping portions at the proximate sides of the cast bearing units, said underlapping portions being adapted to underlap the opposite ends of the girt member, said underlapping portions each having a key extending longitudinally thereof and in exact alignment with each other, the overlapping ends of the girt member each being provided with a keyway, said keyways in the end of the girt being machined in accurate alignment with each other and being adapted to slidably receive the said key in the underlapping portions and means for securing the overlapping ends of the girt to the underlapping portions of the cast bearing unit, said keys in the underlapping portions of the cast bearing units being machined in parallel alignment with the axis of the bearing surfaces in each of the cast bearing units thus insuring that both of the cast bearing units and the girt shall be in accurate alignment with respect to each other.

3. In a loom having side frames and a crankshaft and said crankshaft having a crank throw near each end thereof, means for rotatably mounting the crankshaft in the loom comprising a pair of cast bearing units adapted to be secured to the proximate surfaces of the side frames, each of said cast bearing units having a pair of spaced bearing block portions cast integral therewith, each of said bearing block portions having a semi-circular groove milled therein, the axes

of the said semi-circular grooves being in alignment with each other, said bearing block portions being adapted to rotatably support the crankshaft adjacent opposite sides of the crank throws, semi-circular bearing caps adapted to be secured to the upper surfaces of the bearing block portions to form the upper half of the bearing for rotatably supporting the crankshaft, a rigid member having its ends secured to the proximate sides of the cast bearing units and spanning the distance therebetween, the connection between the ends of the girt and the cast bearing units comprising a key and keyway extending longitudinally of the girt and bearing units.

4. In a loom having side frames and a crankshaft and said crankshaft having a crank throw near each end thereof, means for rotatably mounting the crankshaft in the loom comprising a pair of cast bearing units adapted to be secured to the proximate surfaces of the side frames, each of said cast bearing units having a pair of spaced bearing block portions cast integral therewith, each of said bearing block portions having a semi-circular groove therein, the axes of the said semi-circular grooves being in alignment with each other, said bearing block portions being adapted to rotatably support the crankshaft adjacent opposite sides of the crank throws, semi-circular bearing caps adapted to be secured to the upper surfaces of the bearing block portions to form the upper half of the bearing for rotatably supporting the crankshaft, a rigid member having its ends secured to the proximate sides of the cast bearing units by a key and keyway connection and spanning the distance therebetween and holding all of the bearing grooves in both of the bearing block portions in a straight line.

EDWARD F. BAHAN.
